Primary Examiner — Selina Sikder(74) *Attorney, Agent, or Firm* — Fenwick & West LLP(57) **CLAIM**

We claim the ornamental design for an electronic module, as shown and described.

DESCRIPTION

FIG. 1 is a perspective top view of an electronic module showing my new design.

FIG. 2 is a top view thereof.

FIG. 3 is a front elevational view thereof, the rear being a mirror image; and,

FIG. 4 is a left side elevational view thereof, the right being a mirror image.

In the drawings, the broken lines depict portions of the module which form no part of the claim.

1 Claim, 3 Drawing Sheets(56)
